(57) **CLAIM**

The ornamental design for an electric irrigator as shown and described.

DESCRIPTION

FIG. 1 is a front, left and top perspective view of an electric irrigator showing my design;

FIG. 2 is a bottom, rear, right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1; and,

FIG. 11 is an enlarged view of portion 11 shown in FIG. 1. The broken lines are included for the purposes of illustrating portions of the electric irrigator that form no part of the claimed design.
